UNITED STATES PATENT OFFICE

CONRAD BAUER, OF MOUNT OLIVER, PENNSYLVANIA

VENETIAN BLIND

Application filed October 21, 1927. Serial No. 227,746.

One feature of my invention is a new and improved slatted blind structure.

Another feature is the provision of improved means for guiding the blind in its lowering and raising movements and for the disposal of the blind in either a vertical or inclined position.

I preferably associate the flexible blind with a screen, mounting the two elements on parallel rollers, and I provide new and improved means for locking one of the elements against movement while the other is being raised or lowered.

Other novel features of construction, and also of arrangement of parts will appear from the following description.

In the accompanying drawings, wherein I have illustrated the best embodiment of the principles of my invention now known to me, Fig. 1 is a broken vertical section of a window frame to which my invention is applied, the side of the frame being partially broken away to show the gear mechanism and shifting lever; Fig. 2 is a broken inside elevation of the blind proper showing the slats and their means of connection; Fig. 3 is a section taken along the line 3—3 in Fig. 2; Fig. 4 is a detail showing the means for locking the gear shift lever against accidental movement; Fig. 5 is a detail showing the swivel block and the lifting rod for raising the blind into and supporting it in an inclined position; Fig. 6 is a broken inside elevation showing the lower end of the guide frame and means for locking it in its vertical position; Fig. 7 is a sectional view taken along the line 7—7 in Fig. 6; Fig. 8 is a view similar to Fig. 5 but showing a modified form of locking means; Fig. 9 is a sectional view taken along the line 9—9 in Fig. 8, and Fig. 10 is an enlarged section along line 10—10 in Fig. 1.

Referring to the drawings, 1 represents the side of a window frame and 2 a boxing extending transversely above the window opening.

In the boxing 2 are mounted the transversely disposed and parallel rollers 3 and 4, the former being positioned below the latter. The ends of the rollers are journaled in standard plates such as shown at 5 in Fig. 1. At

one end the rollers have fixedly mounted thereon the pinions 6 and 7, respectively.

The lower roller 3 has wound thereon the length of screen 8 which is preferably of wire mesh provided with a cross bar 9 at its lower end. The vertical edges of the screen and the ends of the bar slide in the vertical guides 10 which are channel members attached to the sides 1 of the window frame. It is evident that by rotating the roller in the one direction the screen 8 may be lowered and a reverse rotation of the roller will raise the screen.

The upper roller 4 has wound thereon the upper portion of the flexible blind comprising the slats 11 and the connector members 12. It is evident that a rotation of the roller 4 in the one direction will lower the blind while a reverse rotation of said roller will raise the blind.

I provide a selective gear mechanism for raising or lowering either the blind or the screen at will; and also for locking the one stationary while the other is being raised or lowered. Thus 13 is a horizontal shaft in the boxing 2 and upon the same is mounted the rocking bar 14 which carries at one side of its axis of motion a pinion 15 which when the bar is moved in one direction, counterclockwise in Fig. 1, comes into mesh with the pinion 7 of the roller 4 and when the bar is moved in the opposite direction comes into mesh with the pinion 6 of the roller 3. 16 is a second pinion continuously in mesh with the pinion 15 and rotatable upon the shaft 13 as an axis. 17 is a sprocket mounted coaxially with the pinion 16 and moving therewith, and 18 is an endless chain which runs over the sprocket 17 and depends behind the side 1 of the window frame, one strand extending through an aperture in the inside facing 19 of the window frame and over a pulley 20 and being exposed within the room so as to be seized by the hand.

The rocking bar 14 is shiftable, so as to bring the pinion 15 into mesh either with the pinion 6 or 7 by means of a shift rod 21 pivotally connected to the inner end of the bar 14 and depending down within the side 1 and facing 19 of the window frame. It

is evident that when the rod 21 is pushed upwardly the pinion 15 will be caused to mesh with the pinion 7 so that by pulling the chain 18 in the proper direction the blind may be raised or lowered, and on the other hand by pulling downwardly on the rod the pinion 15 will be caused to mesh with pinion 6 so that by pulling the chain 18 in the proper direction the screen 8 may be either raised or lowered.

10 The lower end of the bar 21 is bent rearwardly so as to protrude through a slot 22 in the facing 19. 23 represents projections at either side of the slot 22 and intermediate of its vertical length, and the protruding end of the bar 21 is provided with a handle 24 of too great width to pass between such projections. Thus by pulling the end of the rod outwardly so that the handle will clear the projections, the rod may be moved up or down to shift the gear 15. Means, such as the leaf spring 25 are provided to throw the rod inwardly when released so that the handle 24 will move into position either 20 above the projections 23, as shown in Fig. 1, or below the latter, as the case may be, thus locking the rod and the rocking bar 25 against accidental movement.

On the opposite side of its axis of movement from the pinion 15 the end of the bar 14 is provided with a sector-shaped locking finger 26 whose ends are tooth-shaped and so disposed that when the pinion 15 is in mesh with one of the pinions 6 or 7, the locking finger is in engagement with the other of said two pinions, thus locking one roller stationary while the other roller may be rotated.

40 The inner strand of the chain 18 also passes over a roller 27, and the rollers 20 and 27 are mounted on a horizontal bracket 28 which is provided with an upwardly extending arm 29 which is clamped to the stand 5 by a bolt 30 which passes through a horizontal slot 31 in the stand, thus enabling the bracket 28 to be adjusted to suit different 45 depths of window frames.

50 The connector plates 12 which attach the blind slats 11 together may be stamped out of flat metal and are riveted or otherwise secured to the backs of the slats 11, two or more vertical rows of plates being employed. The rear surfaces of the slats 11 are provided with recesses 32 open at the bottom and the plates 12 are provided with a pair of depending spaced apart tongues 33 which are bent up to close the bottom of the recess except for a restricted opening at its center. 55 34 represents a restricted neck which extends upwardly from each plate above the slat and 60 is provided at its upper end with lateral extensions which form trunnions 35. When the slats are assembled to form the blind, the necks of the plates 12 of one slat 11 extend upwardly through the opening in the bottom 65 of the recess 32 of the slat next above and

between the tongues 33 of the plate next above, the trunnions 35 occupying said recess and when the slats hang by their weight said trunnions are journaled within the bent up tongues 33.

70

It is thus seen that the slats are pivotally connected together and when hanging by their weight are spaced apart for the admission of light and air. However when crowded together, the slats interfit so as to 75 provide a tight closure.

80

85 The ends of the slats 11 slidably engage channel guides at either side of the window frame. Thus the upper and arcuate guides 36 are fixed in place and extend forwardly and downwardly from the roller 4 within the boxing 2 and the lower guides formed by the telescoping members 37^a and 37^b have their upper ends pivotally attached to the lower end of the upper guides 36. The lower guide members 37^b are connected together at their lower ends by the cross bar 38, thus forming a lower guide frame which may be vertically positioned within the window opening as shown in Fig. 1, or which may be 90 swung outwardly at the bottom to position the blind in an inclined position.

85

95 39 represents a rod pivotally attached at one end to the guide member 37^a intermediate of the ends of the latter, said rod being slidable within a block 40 which is swivel-mounted on the side 1 of the window frame. A set screw 41 is provided to fix the rod relative to the block. One of said rods is provided at each side of the window frame and are employed to extend the swingable guide frame into an inclined position. The inclination of the frame may be adjusted to the desired angle. By tightening the set screws the blind is maintained in its vertical or inclined position.

100

105 The upper guide members 37^a telescope within the lower guide members 37^b as shown in Figs. 1 and 10, the side flanges of the lower members 37^b being provided with lips 37^c which hold the guide members against lateral displacement but permit a longitudinal sliding movement between the members. Thus the swinging frame may be lengthened or shortened. It is frequently desirable to 110 shorten the frame when it is swung outwardly into an inclined position.

110

115 One of the members, such as 37^b, may be provided with shallow sockets 37^d and the other member with corresponding projections 37^e so as to hold the frame in its extended or shortened condition against accidental movement.

120

125 I provide means for locking the blind in its vertical position.

Thus in Figs. 1, 6 and 7, 42 represents a bar pivotally mounted on the inner face of the cross bar 38 and having its end bent inwardly and notched to form the hook 43 which engages down over the head screw 44 130

125

extending from the member 45 of the window frame. The hook is provided with a lateral extension 46 forming a finger hold.

In Figs. 8 and 9 I show a locking member 47 having a handle at one end and a hook on the other end and pivotally mounted at its center to the cross bar 38. The hook end of the locking member engages a stud 48 on the window frame.

From the foregoing it is obvious that my invention marks a decided advance in flexible blind construction and also in combined blind and screen construction.

The structure of the slatted blind is strong and durable. The use of tapes is avoided by the substitution therefor of simple and inexpensive yet strong and durable metal elements. The connection between the slats is such that they may be caused to interfit and thus form a tight closure impervious to the sunlight and rain or they may separate and thus admit light and air freely.

My mechanism for operating the rollers upon which the blind and screen are wound provides improved means for locking the rollers stationary and preventing one roller from moving while the other is being rotated.

What I desire to claim is:—

1. For use in connection with a window frame provided with a flexible blind, a flexible screen, means for rolling up and unrolling the blind, means for rolling up and unrolling the screen, and selective means comprising a rocking member for bringing either of said rolling up and unrolling means into operative relation; means for locking said rocking member against accidental movement.

2. For use in connection with a window frame provided with a flexible blind, a flexible screen, means for rolling up and unrolling the blind, means for rolling up and unrolling the screen, selective means comprising a rocking member for bringing either of said rolling up and unrolling means into operative relation, and a rod for shifting said rocking member; spring means for locking said rod against accidental movement.

3. For use in connection with a window frame provided with a flexible blind, a flexible screen, means for rolling up and unrolling the blind, means for rolling up and unrolling the screen, selective means comprising a rocking member for bringing either of said rolling up and unrolling means into operative relation, and a rod pivotally connected to the rocking member whereby by raising or lowering the rod the rocking member may be shifted to bring into its operative relation either the blind rolling up and unrolling means or the screen rolling up and unrolling means; means for locking said rod in its raised and lowered positions.

4. For use in connection with a window frame provided with a flexible blind, a flex-

ible screen, means for rolling up and unrolling the blind, means for rolling up and unrolling the screen, selective means comprising a rocking member for bringing either of said rolling up and unrolling means into operative relation, and a depending rod pivotally connected to the rocking member whereby by raising and lowering the rod the rocking member may be shifted to bring into its operative relation either the blind rolling up and unrolling means or the screen rolling up and unrolling means, the window frame being provided with a vertically disposed slotted opening and the end of the rod being bent horizontally to form a handle which protrudes through the slot whereby by raising and lowering the handle the depending rod may be shifted; means for locking said handle at either end of said slotted opening.

5. For use in connection with a window frame provided with a flexible blind, a flexible screen, means for rolling up and unrolling the blind, means for rolling up and unrolling the screen, selective means comprising a rocking member for bringing either of said rolling up and unrolling means into operative relation, and a depending rod pivotally connected to the rocking member whereby by raising and lowering the rod the rocking member may be shifted to bring into its operative relation either the blind rolling up and unrolling means or the screen rolling up and unrolling means, the window frame being provided with a vertically disposed slotted opening having an intermediate obstruction and the end of the rod being bent horizontally to form a handle which protrudes through the opening, whereby by raising or lowering the handle in the slotted opening the rocking member may be shifted; an enlarged extremity on said handle whereby by pulling the handle outwardly relative to the opening the handle is free for vertical movement but when the handle is retracted relative to the opening the intermediate obstruction locks the handle against movement along the opening.

6. For use in connection with a window frame provided with a flexible blind, a flexible screen, means for rolling up and unrolling the blind, means for rolling up and unrolling the screen, selective means comprising a rocking member for bringing either of said rolling up and unrolling means into operative relation, and a depending rod pivotally connected to the rocking member whereby by raising and lowering the rod the rocking member may be shifted to bring into its operative relation either the blind rolling up and unrolling means or the screen rolling up and unrolling means, the window frame being provided with a vertically disposed slotted opening having an intermediate obstruction and the end of the rod being bent horizon-

tally to form a handle which protrudes through the opening whereby by raising or lowering the handle in the slotted opening the rocking member may be shifted; an enlarged extremity on said handle whereby by pulling the handle outwardly relative to the opening the handle is free for vertical movement but when the handle is retracted relative to the opening the intermediate obstruction locks the handle against movement along the opening, and spring-means arranged to hold said handle in its retracted position.

Signed at Mt. Oliver, Pa., this 17th day of October, 1927.

CONRAD BAUER.
